UNITED STATES PATENT OFFICE.

JACOB HANSER, OF OXFORD, OHIO.

VEHICLE-SPRING.

SPECIFICATION forming part of Letters Patent No. 280,613, dated July 3, 1883.

Application filed April 13, 1883. (No model.)

To all whom it may concern:

Be it known that I, JACOB HANSER, of Oxford, in the county of Butler and State of Ohio, have invented a new and Improved Spring for 5 Side-Bar Wagons and Buggies, of which the following is a full, clear, and exact description.

My improved spring consists of two or more flat leaf-springs connected to spring-bars, and also to levers pivoted to said bars, which levers connect with the side bars, respectively, the levers being pivoted to shackles that have play along the spring-bars to compensate for the lengthening and shortening of the springs, making a simple, strong, and compact arrangement for side-bar wagons, as hereinafter 15 fully described.

Reference is to be had to the accompanying drawings, forming part of this specification, in which similar letters of reference indicate corresponding parts in all the figures.

Figure 1 is a transverse section through the side bars, showing the springs and levers in side elevation, and the spring-bar partly in side elevation and partly in longitudinal section. Fig. 2 is a plan of the spring device inverted. Fig. 3 is a section of Figs. 1 and 2 on line *x x*, and Fig. 4 is a perspective view of the shackle used in connecting the levers to the spring-bar.

30 I take a flat-bottomed bar, *a*, of wood, shorter than the distance between the side bars, *b*, and wide enough for applying the flat springs *d* to the margins of the under side, also the levers *e* between said springs, and secure said springs to the opposite margins of the opposite ends, as shown in Fig. 2, by bolting them at *g*, and connecting the levers by means of clips *h*, to which they are pivoted, and which are dovetailed in the attaching-plates *i*, so that they 35 may shift forward and backward a little to compensate for the lengthening and shortening of the springs, and also of the lines between the centers as the body rises and falls. The free 40 ends of the springs *d* are pivoted to the inner

ends of the levers *e* at *j*, and the outer ends of 45 the levers are pivoted at *k* to shackles *l* of the side bars, *b*.

In order that the levers *e* may be in line with each other, and at the same time to enable the springs *d* to have greater length than 50 the distance between the fulcrum-shackles *h* would allow, the said springs are placed as far apart on the bar *a* transversely as the space required for the fulcrum-shackles, and the levers are bent at *m* to the right and left hand 55 to coincide with the springs, respectively. I use springs of two or more leaves, according to the power required, making the upper leaves or plates the long ones and connecting the levers to them, because the thrust of the weight 60 is downward on them. The plates *i*, in which the lever-shackles *h* are fitted, are bolted to the spring-bar by bolts *n*.

It will be seen that by the adjustable contrivance of the lever-fulcrums the side bars 65 are relieved of lateral thrusts, to which they would otherwise be subject, and by the substantial backing the bar *a* affords to the springs they will be much less liable to break by the 70 rebound of the body, which is often the most destructive to the springs.

Having thus described my invention, what I claim as new, and desire to secure by Letters Patent, is—

1. The levers *e*, in combination with side 75 bars, *b*, springs *d*, and spring-bar *a*, said levers being connected to the spring-bar by adjustable fulcrums *h*, substantially as described.

2. The springs *d*, arranged on the opposite 80 ends of the spring-bar, with spaces between them for the lever-fulcrums, and the levers arranged in line with each other, and bent at *m* to connect with said springs, substantially as described.

JACOB HANSER.
